US00D835262S

(12) **United States Design Patent** (10) Patent No.: **US D835,262 S**
(45) Date of Patent: ** Dec. 4, 2018

(54) **INTRAVENOUS CATHETER ASSEMBLY**(71) Applicant: **Becton, Dickinson and Company**,
Franklin Lakes, NJ (US)(72) Inventors: **Jonathan Karl Burkholz**, Salt Lake
City, UT (US); **Ralph L. Sonderegger**,
Farmington, UT (US); **Bart D.
Peterson**, Farmington, UT (US); **Bin
Wang**, Sandy, UT (US); **Kelvin Chai**,
Shanghai (CN)(73) Assignee: **Becton, Dickinson and Company**,
Franklin Lakes, NJ (US)(**) Term: **15 Years**(21) Appl. No.: **29/580,127**(22) Filed: **Oct. 5, 2016**(51) LOC (11) Cl. **24-02**

(52) U.S. Cl.

(57) **CLAIM**

The ornamental design for an intravenous catheter assembly, as shown and described.

DESCRIPTION

FIG. 1 is a perspective front, top and side view of an intravenous catheter assembly.

FIG. 2 is a perspective front, top and side view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

1 Claim, 6 Drawing Sheets
